CLAIM

I claim the ornamental design for a display screen with financial institution navigation interface, as shown in the drawings.

DESCRIPTION

FIG. 1 is a first image in a sequence for a display screen with a financial institution navigation interface showing the new design;

FIG. 2 is the second image thereof;

FIG. 3 is the third image thereof; and,

FIG. 4 is the fourth image thereof.

The broken-line rectangle illustrates the perimeter of a display screen. The broken lines form no part of the claimed design. The appearance of the transitional graphical user interface sequentially transitions between the images shown in FIGS. 1-4. The process or period in which one image transition to another image forms no part of the claimed design.
